RENÉ EDOUARD DE WAELE, OF PARIS, FRANCE.

SUBMARINE TOY.

1,328,867.

Specification of Letters Patent. Patented Jan. 27, 1920.

Application filed August 8, 1918. Serial No. 248,954.

To all whom it may concern:

Be it known that I, RENÉ EDOUARD DE WAELE, a subject of the King of the Belgians, resident of Paris, France, post-office address 67 Rue Caulaincourt, Paris, France, have invented a new and useful Submarine Toy, which submarine toy is fully set forth in the following specification.

This invention relates to submersible 10 toys; and it resides in the provision of an improved toy of the character indicated in which the generation of gas is brought about by the action of the water on a chemical substance, so that when the toy 15 has sunk, its specific weight is modified by the formation of the gas, and it is caused to ascend until it floats on the surface of the water.

The present invention comprises a water 20 ballast chamber normally empty of water, rendering possible navigation on the surface under the action of a suitably driven propeller, the ballast chamber being adapted to communicate at its base with the 25 water and being provided at its top with a valve for controlling an opening communicating with the atmosphere. The water which gradually fills the water ballast chamber, as the toy sinks, comes in contact 30 with and raises a second valve which normally closes the upper part of a calcium carbide cartridge, the raising of this second valve closing the first valve and enabling water to come into contact with the carbide. 35 The acetylene gas thereby generated forces the water contained in the water ballast chamber to escape, owing to which the boat is lightened and rises to the surface, the propeller being held stationary by an adjustable device when the toy strikes the 40 bottom of the basin or other receptacle in which it is being used.

An embodiment of the invention is illustrated in the accompanying drawings in 45 which:

Figure 1 is a longitudinal, vertical section of the improved submarine toy;

Figs. 2 to 4 are sections on the lines A—A, C—C, B—B, respectively, of Fig. 1; and 50 Fig. 5 shows two half cross-sections of the submarine brought together.

The submarine may be decorated outside in any suitable manner, and may have any shape and form suitable for the toy.

The propulsion of the submarine is effected by any desired mechanism, for instance by a spring motor *a* which can be wound by a key *b*, and which is connected through suitable gearing to drive the shaft *c* of the propeller *d*. This feature, however, forms no part of the invention, which resides in the means whereby the submerging of the toy and its subsequent rise to the surface of the water are automatically accomplished.

At some suitable part of the boat, there is provided within the hull a ballast tank or chamber *e* which may be put in communication with the water in the basin, tub or other receptacle wherein the toy is being used, by way of a rearwardly-extending pipe or conduit *f* having a removable terminal plug *f'*, said pipe opening through the bottom of the hull, as shown. This tank is normally empty of water, however, the weight of the boat being such that the water line under ordinary conditions will occupy substantially the relative position indicated by the dotted line X—Y in Fig. 1, at which time the boat can travel on the surface.

In the upper portion of the tank, a frame *g* is arranged, which normally supports a valve *h* provided with upstanding pins or projections *i*. This valve *h* is located within an open-topped chamber or neck *j* and directly beneath a disk *n* which is fastened to the lower end of the stem *m* of an air valve *l*, carried by a cover member *k*, the latter being utilized to close the top of chamber *j*. Said chamber *j* is likewise mounted upon the frame *g* which also serves to support a cartridge *o* containing calcium carbide or some other suitable chemical substance or substances which, on being brought into contact with water, will generate a gas. Valve *h* forms a cover or closure for this cartridge, and is of a buoyant nature, so that when the tank is filled with water to the proper height, the water will lift off the valve from the end of the cartridge and raise it upward until its pins *i* strike against the disk member *n* of the air valve *l*. Disk *n* normally rests in lowered position upon suitable depending supports carried by cover *k*, and in such position causes valve *l* to open the air vent. The upward movement of disk *n*, produced as just described, entails a similar movement

of the air valve which results in the closing of the vent.

In use, the boat is placed in the water with its various component parts occupying 5 the positions represented in Fig. 1; but with the plug *f*' removed if submergence is desired. During the movement of the boat, water enters and gradually fills the ballast tank through pipe *f*, the weight of the boat 10 being increased by the incoming water until complete submergence takes place, this occurring at about the time when the level of the water reaches the cartridge top or valve *h*. As the water level continues to rise, the 15 valve *h* will be lifted up and, in its turn, raises the valve *l*, thereby admitting water to the contents of the cartridge and at the same time closing the air vent. Acetylene gas is thereby generated, and, as it fills the 20 space between the water and the top of the tank, forces out from the tank the water through the pipe *f*, whereupon the generating action ceases. This has the obvious result of lightening the weight of the boat, 25 which will rise to the surface and continue its progress, which was automatically terminated by the submergence of the boat so as to avoid possible injury to the bottom of the boat caused by rubbing against the more 30 or less rough bottom of the tub.

To effect the automatic stoppage of the boat when sinking, means is provided for engagement with the propeller in a manner to arrest its rotation. In the construction 35 illustrated, this stopping device is formed by the rudder *p*, which is so mounted as to be capable of a vertical sliding movement, and is so proportioned that in its normal position it projects slightly below the keel of 40 the boat, so that it will touch bottom ahead of the keel. When this takes place, the rudder will be forced upward into engagement with the blades of the propeller and, in consequence, will prevent it from turning. The 45 rudder will resume its usual position, of course, during the ascent of the boat.

The above-described operations continue indefinitely, succeeding one another in the order indicated, until the supply of chemical is completely exhausted.

I claim as my invention:—

1. In a toy submarine boat, the combination of a propeller, and driving mechanism therefor; means for automatically effecting 55 submergence of the boat; and means for automatically terminating the movement of the propeller during submergence.

2. In a toy submarine boat, the combination of a propeller, and driving mechanism 60 therefor; means for automatically effecting submergence of the boat; and means for automatically locking the propeller against rotation during submergence.

3. In a toy submarine boat, the combination of a propeller, and driving mechanism 65

therefor; means for automatically effecting submergence of the boat; and a member movable automatically into engagement with the propeller during submergence, to lock it against operation. 70

4. In a toy submarine boat, the combination of a propeller, and driving mechanism therefor; means for automatically effecting submergence of the boat and its subsequent return to the surface; and means operable 75 automatically to stop the propeller during submergence and thereafter to permit it to start during the ascent of the boat.

5. In a toy submarine boat, the combination of a propeller, and driving mechanism 80 therefor; means for automatically effecting submergence of the boat and its subsequent return to the surface; and a member movable automatically during submergence to lock the propeller against rotation, and during 85 ascent of the boat to unlock said propeller.

6. In a toy submarine boat, the combination of a propeller, and driving mechanism therefor; means for automatically effecting 90 submergence of the boat and its subsequent return to the surface; and a member engageable automatically with the propeller blades during submergence to arrest the movement of the propeller, but releasable 95 automatically therefrom when the boat ascends.

7. In a submersible toy, the combination of a ballast chamber having a water inlet; and a container for a gas-generating substance suspended in the upper portion of the ballast chamber and having a normally-closed, removable cover which is lifted off by the water in the ballast chamber when the level thereof rises to the proper height, 100 thereby to permit access of the water to said gas-generating substance. 105

8. In a submersible toy, the combination of a ballast chamber having a water inlet; a container for a gas-generating substance 110 suspended in the upper portion of the ballast chamber and having a normally-closed, removable cover which is lifted off by the water in the ballast chamber when the level thereof rises to the proper height, thereby 115 to permit access of the water to said gas-generating substance; and an air-escape valve on said ballast chamber adapted to close automatically substantially at the commencement of the gas-generating operation. 120

9. In a submersible toy, the combination of a ballast chamber having a water inlet; a container for a gas-generating substance suspended in the upper portion of the ballast chamber and having a normally-closed, removable cover which is lifted off by the water in the ballast chamber when the level thereof rises to the proper height, thereby to permit 125 access of the water to said gas-generating substance; and a normally-open air-escape valve 130

on said ballast chamber adapted to be moved into closed position by said cover when the latter is lifted off by the water.

10. In a submersible toy, the combination 5 of a ballast chamber having a water inlet; a container for a gas-generating substance suspended in the upper portion of the ballast chamber and having a normally-closed, removable cover which is lifted off by the 10 water in the ballast chamber when the level thereof rises to the proper height, thereby to permit access of the water to said gas-generating substance; and a normally-open air escape valve on said ballast chamber dis- 15 posed directly above said cover, the latter being provided with upstanding projections adapted to engage said valve and force it into closed position when the cover is raised by the water.
20. 11. In a toy submarine boat, the combination of propelling mechanism; a ballast chamber having an opening through which water can enter to effect submergence of the boat; a container in said chamber for a 25 chemical substance which will generate a gas on being brought into contact with the water, to drive out the water from said chamber and thereby cause the ascent of the boat; and means for automatically stopping 30 the propelling mechanism during the sinking of the boat.
12. In a toy submarine boat, the combination 35 of propelling mechanism; a ballast chamber having an opening through which water can enter to effect submergence of the

boat; a container in said chamber for a chemical substance which will generate a gas on being brought into contact with the water, to drive out the water from said chamber and thereby cause the ascent of the boat; 40 and means for automatically arresting the propelling mechanism during the sinking of the boat, and for thereafter releasing it when the boat rises.

13. In a toy submarine boat, the combination 45 of a propeller, and driving mechanism therefor; means for automatically effecting submergence and subsequent ascent of the boat; and a vertically-movable rudder located directly beneath the propeller and 50 adapted to be forced upward on striking the bottom when the boat sinks, so as to engage the propeller blades and thereby arrest the rotation of the propeller.

14. In a toy submarine boat, the combination 55 of propelling mechanism; means for automatically effecting submergence and subsequent ascent of the boat; and a vertically-movable rudder adapted to be forced upward on striking the bottom when the 60 boat sinks and acting to automatically stop the propelling mechanism during such upward movement.

In testimony whereof I have signed this specification in the presence of two sub- 65 scribing witnesses.
